BRUSH ASSEMBLY

Herman A. Steiert, New Centerville, Pa.

Application November 14, 1939, Serial No. 304,298

4 Claims. (Cl. 15—191)

This invention has to do with brushes and is concerned primarily with the mode of incorporating bristles into a brush assembly.

At the present time there is in use apparatus, such as street cleaning equipment, that includes a brush head that is mounted on a rotating shaft and from which project bristles. Certain conditions of usage which must be accommodated by this equipment require that the bristles be angularly carried by the brush head so that the effective ends of some of the bristles are disposed exteriorly of the periphery of the brush head. This invention is made with such an arrangement particularly in mind, because the foremost objective in view is the provision of a novel arrangement of assembling the bristles in a brush head which readily adapts itself to this angular disposition of the bristles.

The bristles of brushes of the type with which this invention is concerned, such as street cleaning brushes, ordinarily are made from appropriate metal such as steel. The heads with which they are assembled generally are of a multiple part construction consisting of a main body part to which is clamped one or more bristle carrying parts.

Heretofore it has been the practice to form one of the bristle carrying head parts with apertures designed to have the bristles passed therethrough. A single piece of steel wire is bent into hairpin formation and the legs thereof passed through a pair of these apertures, the bend of the hairpin being clamped between the bristle carrying and main body parts. This known arrangement presents certain disadvantages which are intended to be obviated by the present invention.

In the first place, considerable difficulty is experienced in assembling the bristles in that each bristle must be threaded through its required opening. Furthermore, the bend of each pair of bristles has been found to be an undesirable factor when subject to the clamping between the parts of the brush head. Perhaps the greatest difficulty has been experienced in replacing worn bristles.

With the above noted conditions in mind this invention has in view, as an important object, the provision of a brush assembly of the character above noted in which each of the bristle carrying parts of the brush head is formed with a plurality of openings each of which is designed to receive a unit of bristles. Each bristle unit consists of a plurality of metallic bristles which are joined together at one end, and to a head element by an appropriate metal fusion process such as welding.

More in detail this invention contemplates an arrangement in which each opening in the bristle carrying part of the brush head is surrounded by a countersink that is designed to receive the head

of each bristle unit. The openings in the bristle carrying part may be disposed at an appropriate angle for causing the bristles to project therefrom at the required angle with respect to the brush head. Each bristle unit comprises a washer formed with a central opening in which extremities of the bristles are received. The bristles are joined to this washer at the required angle, as by welding. Thus when the heads of the bristle units are positioned in the countersinks the bristle carrying parts of the brush head may be securely clamped to the main body part of the brush head to provide a firm anchorage of the bristle units therein.

15 Various other more detailed objects and advantages of the invention will in part become apparent, and in part be hereinafter stated, as the description of the invention proceeds.

The invention, therefore, comprises a brush assembly consisting of a brush head made up of a main body part and one or more bristle carrying parts, together with means for clamping the bristle carrying parts to the main body part. The bristle carrying parts are formed with angularly disposed openings extending therethrough, and which openings terminate in countersinks on the inner face of the brush part. Assembled in each opening is a bristle unit comprising a plurality of bristles that are welded together and to a washer-like head. This head is received in the countersink, while the bristles extend through the opening in the bristle carrying part.

For a full and more complete understanding of the invention reference may be had to the following description and accompanying drawing, wherein—

Figure 1 is a perspective view of a bristle carrying part of the brush head with certain of the bristle units assembled therein. This view also develops the means for clamping this part to the main body part of the brush head.

Figure 2 is a side view, partly in section, of one end of a bristle unit developing the manner in which the bristles are joined to the head of the bristle unit.

Figure 3 is an elevational showing taken as a section through one of the bristle carrying parts of the brush head, and

Figure 4 is a side elevational showing of a brush assembly in which the bristles are anchored therein in accordance with the precepts of this invention. In this view each bristle unit is represented diagrammatically.

55 Referring now to the drawing, wherein like reference characters denote corresponding parts, and first more particularly to Figure 4, a brush assembly is shown as comprising a brush head referred to in its entirety by the reference character H, which carries a plurality of bristle units

each of which is referred to in its entirety by the reference character U.

The brush head H comprises a main body part 10 which is carried at one end of a shaft 11 which rotates when the brush is used. This main body part 10 is formed with a plurality of openings 12, which may be threaded for a purpose to be hereinafter pointed out. Carried on the lower face of the main body part 10 are a plurality of bristle carrying head parts 13. Each of these head parts 13 is formed with a required number of openings 14 through which fastening means, such as headed bolts 15, pass. These bolts 15 are threaded, as shown at 16, and these threaded ends 16 are designed to be screwed into the threaded openings 12 in the main body part 10 to clamp each of the bristle carrying parts 13 thereto. As shown more particularly in Figure 3, each of the bristle carrying parts 13 is cut away adjacent to the openings 14 to accommodate the heads of the bolts 15.

Referring now more particularly to Figures 1 and 3, each of the bristle carrying parts 13 is shown as formed with a plurality of apertures or passageways 17 which are angularly disposed with respect to the faces of the bristle carrying part 13. The upper face of each bristle carrying part 13 is designed for engagement with the main body part 10 of the brush head, and is designated 18. This face 18 is formed with a plurality of countersinks each of which is positioned at the upper extremity of the aperture 17, these countersinks being designated 19.

One of the bristle units U comprises a plurality of bristles 20 which preferably are made from a steel wire of appropriate cross section such as a flat steel wire. These bristles 20 are closely bunched at one end and received in an opening 21 (see Figure 2) which is formed with a washer-like head 22. With the ends of the bristles so bunched and received in the openings 21 an appropriate metal fusion process, such as welding, is available of to join the various bristle ends together and to the head 22, the welded joint being shown at 23.

Each of the washer-like heads 22 is designed to be snugly received in one of the countersinks 19, and in joining the washer-like head 22 to the bristles an angular relation between the two will be established that corresponds to the angular disposition of the aperture 17 with respect to the faces of the bristle carrying part 13. Each bristle unit is positioned so that the bristles 20 extend through the apertures 17 with the washer-like heads 22 received in the countersinks 19. The bristle carrying part 13 is then assembled with the main body part 10 so that the face 18 contacts the latter. The bolts 15 are then tightened in the manner above described to complete the assembled relationship in which a firm anchorage for each bristle unit is provided.

When it becomes necessary to replace any bristle unit it is obvious that the replacement may be readily carried out by removing the part 13 which carries the worn bristle unit, removing the latter therefrom by merely withdrawing the head 22 from the countersink 19, and drawing the bristles 20 upwardly through the apertures 17. A new bristle unit may then be positioned in the manner above described and the part 13 again clamped to the main body part 10 of the brush head.

While a preferred specific embodiment of the invention is hereinbefore set forth it is to be clearly understood that the invention is not to be limited to the exact construction illustrated and described, because various modifications of these details may be provided in putting the invention into practice within the purview of the appended claims.

I claim:

1. A brush assembly of the character described comprising a brush head consisting of a main body part and a bristle carrying part having meeting faces clamped together, means for holding said parts together, said bristle carrying part being formed with an aperture inclined to a normal to said meeting face and terminating on said meeting face in a countersink having a bottom wall parallel to said meeting face, and a bristle unit comprising a plurality of juxtaposed metallic bristles, a flat metallic washer-like head surrounding said bristles at one end and tilted with respect to said bristles at an angle corresponding to the angle of inclination of said aperture to said faces, and a fused metal joint between said bristles and said head, said head being received in said countersink, and portions of said bristles adjacent said head arranged in said aperture at its angle of inclination.

2. A brush assembly of the character described comprising a brush head consisting of a main body part and a bristle carrying part having meeting faces clamped together, means for holding said parts together, said bristle carrying part being formed with an aperture inclined to a normal to said meeting face and terminating on said meeting face in a countersink having a bottom wall parallel to said meeting face, and a bristle unit comprising a plurality of juxtaposed steel bristles, a flat steel washer-like head surrounding said bristles at one end and tilted with respect to said bristles at an angle corresponding to the angle of inclination of said aperture to said faces, and a welded joint between said bristles and said head, said head being received in said countersink, and portions of said bristles adjacent said head arranged in said aperture at its angle of inclination.

3. In a brush assembly of the character described, a bristle unit comprising a plurality of metallic bristles bunched together at one end, a flat head formed with an opening of greater area than a cross-section of said bunched bristles, said bunched bristles being received in said opening with said head tilted at an angle of less than 90° with respect to said bristles, and a fused metal joint joining said bunched ends of the bristles together and to said head.

4. In a brush assembly of the character described, a bristle unit comprising a washer-like head formed with a central opening, a plurality of steel bristles bunched together at one end with the bunched ends received in said opening, the axis of said bunched bristles being inclined with respect to a normal to said head, and a welded joint joining the bunched ends of said bristles together and to said head with the axis of said bunched bristles being inclined with respect to a normal to said head.
